RADIO RECEIVING APPARATUS

Emerick Toth, Flushing, N. Y., and William H. Cooper, Passaic, N. J., assignors to Pilot Radio Corporation, Long Island City, N. Y., a corporation of New York

Application November 12, 1935, Serial No. 49,334

4 Claims. (Cl. 250—16)

This invention relates to improvements in radio receiving apparatus, being particularly directed to a visual resonance device and mounting thereof in the receiver cabinet in association with the speaker assembly.

Broadly, it is an object of this invention to provide for a visual resonance device adapted to be disposed for observation at the front of a radio receiver cabinet, the visual resonance device being assembled and mounted within the cone of a loud speaker assembly, whereby to provide for prominent disposition of the indicator device in the cabinet and at the same time to provide for compensation with respect to the response of the loud speaker to various ranges of frequencies.

Up to the present time, one of the difficulties in radio receiver construction lies in the fact that visual resonance indicators, particularly the cathode type mechanism to indicate the attainment of optimum conditions within the receiver, has been disposed in various positions normally in unsymmetrical relationship with respect to the visible elements of a radio receiver; further, it has been found that a normal loud speaker of a radio receiver delivers in its response unwanted variations from the normal with respect to the higher frequency ranges.

With respect to these two deficiencies, it is the object of this invention to provide for a symmetrical and prominent disposition of the visual resonance device with respect to the cabinet and at the same time to provide for a constructional assembly of such visual resonance device in relation to the cone of the loud speaker assembly as to cause a diversion from the normal path of sounds from the response of the loud speaker to the higher frequency ranges, as to produce through this compensation a desired effect, as, for example, a specific response curve having a straight line function.

Specifically, it is an object of this invention to provide for the disposition within the cone section of a loud speaker assembly of a visual resonance indicator assembly of such construction as to provide for prominent symmetrical dispositioning of the visible resonance indicator at the face of the cabinet, while at the same time, due to its location within the cone of the loud speaker assembly, provide for directional displacement of the sound waves, developed in the speaker, particularly those in the high frequency ranges, whereby irregularities or peaks of the normal loud speaker curves as to the response for such high frequency ranges may be com-

pensated for and reduced to provide a substantial straight line curve for response characteristics.

These and other advantages, capabilities and features of the invention will appear from the subjoined detailed description of one specific embodiment thereof illustrated in the accompanying drawing, in which

Figure 1 is a side elevation in section of the device.

Figure 2 is a front elevation.

Figure 3 is a graphical representation of the field pattern normally produced through a loud speaker unit.

Figure 4 is a graphical representation of the field pattern in the loud speaker unit assembly, incorporating the applicants' device.

Figure 5 is a graph showing the response at various frequencies for a loud speaker unit.

Figure 6 is a graph showing the response at various frequencies for a loud speaker unit incorporating the applicants' device.

Referring to the reference characters in the drawing, numeral 10 represents the front panel of a radio receiver having a latticed grill 11, behind which is disposed a loud speaker assembly 12 incorporating the armature unit 12, the vibrating cone 13, and the peripheral supporting cone ring 14; the speaker assembly being mounted adjacent the baffle board 15 disposed to the rear of the panel about the periphery of the grill.

Within the hollow of the cone 13 and substantially centrally thereof, and concentric therewith, there is disposed a metallic conical casing 16, the same being firmly mounted by means of radially extending brackets 17, the ends 18 of which are attached to the outer surface thereof, and the free ends 19 of which are fastened between the cone ring 14 and the baffle board 15. Within the metallic conical casing 16 there is disposed a visual resonance tube 20, of the cathode ray type, the same being mounted in socket 21, disposed within the restricted aperture of cone 16, from which socket extends cable 22 leading to an electrical source in the socket for actuating the visual resonance tube.

The head 23 of the visual tuning tube extends forwardly of the large aperture of the conical casing 16 and passes through aperture 24 formed centrally of the grill 11, the aperture 24 being bounded by decorative bead 25, so as to present for ready observation the visual ray or beam developed in the electrode unit 26 disposed in said bead.

In this manner, the visual resonance medium is disposed for ready observation in a most central location with respect to the front panel of a radio

receiver, while at the same time eliminating the necessity of additional space or mounting of the same through the application of the area within the hollow of the cone of the loud speaker; in 5 addition thereto, the metallic cone 16, in which the visual resonance tube is mounted, serves for an added function, to provide an acoustic compensator for the purpose of minimizing the distortion effect normally developed in the response 10 of a loud speaker as relates to the sound beam effect developed at high frequencies.

With reference to Figures 3 and 4, the frequency distribution or the field pattern in the normal loud speaker, shown in Figure 3, indicates 15 the production of an unwanted, unsymmetrical high frequency beam, whereas with the application of the applicants' device, as indicated in Figure 4, the high frequency beam is symmetrical with respect to the remaining lower frequency 20 beams and is more evenly distributed.

As shown graphically in Figures 5 and 6, in the relative response-frequency curves, the normal curve of a loud speaker, as shown in Figure 5, indicates the presence of peaks, particularly at high 25 frequencies, with the resultant distortion; to minimize this peak, the application of the conical casing, as indicated, provides a compensating effect with the result that the curve at the high frequencies is flattened to bring about a substantially 30 straight line response-frequency curve.

It is obvious that various changes and modifications may be made to the details of construction without departing from the general spirit 35 of the invention as set forth in the appended claims.

We claim:

1. In a device of the class described, in combination with a cabinet incorporating a loud speaker assembly mounted on the panel thereof, a visual 40 resonance indicator disposed within the cone of the loud speaker assembly and projecting through the panel, and a supporting casing for said visual

resonance indicator mounted on the panel and having a wall formation extending at an angle different from that of the cone of the loudspeaker to provide a change in the distribution for certain ranges of the high frequency response of the 5 speaker.

2. In a device of the class described, in combination with a cabinet incorporating a loud speaker assembly mounted adjacent the front panel thereof, a visual resonance indicator disposed within the cone of the loud speaker assembly, and visible at the front panel, and a supporting casing for said visual resonance indicator mounted within the cone of the loud speaker, to provide a change 10 in the distribution for certain ranges of the high 15 frequency response of the speaker.

3. In a device of the class described, in combination with a cabinet incorporating a loud speaker assembly disposed adjacent the grilled front panel thereof, a casing disposed within the cone of said 20 loud speaker assembly, and a visual resonance indicator supported in said casing, said visual resonance indicator being disposed as to project in the grill of the front panel for observation and the supporting casing being so formed and positioned as to rearrange the field pattern with respect to the frequency distribution normally developed in the loud speaker.

4. In a device of the class described, in combination with a cabinet incorporating a loud speaker 30 assembly mounted on the panel thereof, a visual resonance indicator disposed within the cone of the loud speaker assembly and projecting through the panel, and a supporting casing for said visual 35 resonance indicator mounted within the cone of the loud speaker and having a wall formation extending at an angle different from that of the cone of the loud speaker, to provide a change in the distribution for certain ranges of the high 40 frequency response of the speaker.
